UNITED STATES PATENT OFFICE.

HENRY B. SOMMER, OF PHILADELPHIA, PENNSYLVANIA.

DESIGN FOR A JEWELRY-BOX.

SPECIFICATION forming part of Design No. 16,254, dated September 15, 1885.

Application filed March 3, 1885. Term of patent 3½ years.

To all whom it may concern:

Be it known that I, HENRY B. SOMMER, a citizen of the United States, residing in the city and county of Philadelphia, State of Pennsylvania, have invented and produced a new and original Design for a Jewelry-Box, of which the following is a specification, reference being had to the accompanying drawings, forming part thereof.

10 The figures are perspective views of a jewelry-box embodying my design, the same being respectively closed and open.

Similar letters of reference indicate corresponding parts in the two figures.

15 The leading feature of my design for a jewelry-box is the body of the same of the form of a book, with a fluffy top, bottom, and back, and plain front and sides.

A represents the body of a jewelry-box, consisting of a top, a, bottom b, front c, and sides d, the latter being divided at e, the several

parts being so shaped that the body simulates a book. The top, bottom, and back have fluffy surfaces, and the sides d and front e have plain surfaces. The fluffy surfaces of 25 the top, bottom, and back are continuous.

I claim—

1. A design for a jewelry-box of the form of a book, having a top, bottom, back, front, and sides, the top, bottom, and back having fluffy 30 surfaces continuous of each other, as shown and described.

2. A design for a jewelry-box of the form of a book, having a top, bottom, back, front, and sides, the top, bottom, and back having fluffy 35 surfaces, and the front and sides having plain surfaces, as shown and described.

HENRY B. SOMMER.
